United States Patent

Des. 237,855
Patented Dec. 2, 1975

237,855

CANISTER WITH LID OR SIMILAR ARTICLE

Walter B. Achenbach, Toledo, Ohio, assignor to
Owens-Illinois, Inc., Toledo, Ohio

Filed Oct. 9, 1973, Ser. No. 404,770

Term of patent 14 years

The term of this patent subsequent to May 13, 1989,
has been disclaimed

Int. Cl. D9—02; D7—07
U.S. Cl. D7—79

FIG. 2

FIG. 1

FIG. 4

FIG. 3

FIG. 5

FIG. 6

FIG. 1 is an elevational view of a canister with lid or similar article embodying my new and ornamental design in the size and proportions of a rock candy jar;

FIG. 2 is a top plan view thereof;

FIG. 3 is a bottom view thereof;

FIG. 4 is a central sectionalized view of the canister with lid in FIG. 2 taken along section lines 4—4 in that figure;

FIG. 5 is an elevational view, partly in section, of a canister with lid or similar article embodying my new and ornamental design in the size and proportions of a coffee jar; and

FIG. 6 is an elevational view, partly in section, of a canister with lid or similar article embodying my new and ornamental design in the size and proportions of a stick candy jar.

I claim:

The ornamental design for a canister with lid or similar article, as shown and described.
